UNITED STATES PATENT OFFICE.

SAMUEL N. GOODMAN, OF PHILADELPHIA, PENNSYLVANIA.

EXERCISING-MACHINE.

SPECIFICATION forming part of Letters Patent No. 341,231, dated May 4, 1886.

Application filed February 23, 1886. Serial No. 192,853. (No model.)

To all whom it may concern:

Be it known that I, SAMUEL N. GOODMAN, a citizen of the United States, residing in Philadelphia, Pennsylvania, have invented 5 certain Improvements in Exercising Apparatus, of which the following is a specification.

My invention relates to that class of exercising apparatus in which an inflated bag or ball is supported at about the height of a man's head by means of upper and lower flexible cords and straps, the object of my invention being to provide an exercising device of this character with a supporting structure or carrier which will dispense with the necessity 15 for permanent attachments to the floor or ceiling, and will enable the apparatus to be set up in any desired portion of a room or apartment, or permit it to be readily transported from place to place.

20 In the accompanying drawings, Figure 1 is a perspective view of the exercising apparatus and a carrying or supporting structure therefor in accordance with my invention. Fig. 2 is a side view on a larger scale than Fig. 1; 25 and Figs. 3 and 4, diagrams on a reduced scale, showing modifications of my invention.

An inflated rubber ball or bag supported at about the height of a man's head by means of upper and lower elastic cords and straps 30 is an exercising device now much in vogue, the ball being struck by the fists, and being caused to return under the influence of the elastic cords.

Usually the device consists simply of the 35 inflated ball or bag A, the upper and lower elastic cords, B B, connected thereto, and upper and lower straps, D D, connected to screw eyes or hooks secured to the floor and ceiling of the room in which the device is set up.

40 The blows upon the ball are transmitted to the floor and ceiling with such force as to cause shocks or jars, which prove a serious annoyance, and are frequently a source of damage to the building, in the way of loosening and shaking down the plastering. The im-

proved supporting structure or carrier forming the subject of my invention dispenses with these floor and ceiling connections, and consists, essentially, of a heavy base, F, a post or 45 standard, G, secured to and projecting upward therefrom, and upper and lower bars, H, secured to and projecting from said up-

right post or standard at such relative distances above the base as to provide a proper means of attachment for the upper and lower 55 straps, D D.

In the present instance the bars H have at their inner ends sockets a, adapted to the post G, so that said bars are adjustable to any desired height, being secured in position after 60 adjustment by means of a set-screw, b, and the straps D are adapted to eyes e on screw-stems f, which pass through openings in caps g on the outer ends of the bars H, and are provided with nuts i above and below the cap, 65 so as to permit the tension of the elastic cords B to be varied as desired.

In order to stiffen the post G, and prevent the upper end of the same from vibrating under the influence of the blows delivered upon 70 the ball A, guys m extend from the eyes at said upper end of the post to eyes upon the base F, these guys having suitable tightening-nuts, n.

It will be evident that a supporting structure such as described effectually overcomes 75 the objections hereinbefore mentioned as incident to the usual method of supporting the ball, the improved structure being self-supporting and portable, so that it can be readily set up wherever desired and stowed out of 80 the way when not in use.

To render the device more compact when not in use, the bars H may, if desired, be hinged so as to fold in against the standard G. The supporting structure may have two posts instead of one, as shown in Fig. 3, for instance, each post having a separate base, as shown by full lines in said figure, or a single base common to both posts being used, as shown by dotted lines. The single post is preferred, 90 however, as permitting greater freedom of movement on the part of the person using the apparatus. For gymnasium use each post may have a series of pairs of projecting bars, H, as shown in Fig. 4, for instance, so that 95 the apparatus can be used by more than one person.

The post G and bars H are preferably of wrought-iron pipe, so as to possess the desired lightness without sacrifice of strength. 100

I claim as my invention—

1. The combination of the ball A and its elastic attachments with a self-supporting structure having a weighted base portion and

upper and lower bars, to which said attachments are connected, all substantially as specified.

2. The combination of the ball and its elastic attachments with a supporting structure comprising a weighted base, a vertical post, and projecting bars, to the outer ends of which said attachments are connected, all substantially as specified.
3. The combination of the ball and its elastic attachments with a supporting structure comprising the weighted base, the upright post, projecting bars carrying the elastic attachments of the ball, and guys, whereby the

upper end of the post is connected to the outer 15 portion of the weighted base, all substantially as specified.

4. The combination of the bars H of the supporting structure, the ball and its elastic attachments, the eyebolts f, and adjusting-nuts 20 i thereon, all substantially as specified.

In testimony whereof I have signed my name to this specification in the presence of two subscribing witnesses.

SAMUEL N. GOODMAN.
